METALLIC COATING RECOVERING DEVICE

Maxime J. Brizard, San Francisco, Calif.

Application April 22, 1935, Serial No. 17,587

2 Claims. (Cl. 183—70)

This invention relates to improvements in metallic coating recovering devices.

The principal object of the invention is to produce a device which will recover metallic dust and prevent the same from being picked up by air currents and dissipated over a wide area.

A further object is to produce a device which may be employed with the ordinary printing machinery wherein such metallic dust is used.

Another object is to produce a device which is economical to manufacture.

A still further object is to produce a device which may be readily cleaned, and certain parts renewed without shutting down for any appreciable length of time.

Other objects and advantages will be apparent during the course of the following description.

In the accompanying drawing forming a part of this specification and in which like numerals are employed to designate like parts throughout the same,

Fig. 1 is a top plan view of my device,

Fig. 2 is a side elevation of Fig. 1, showing portions thereof broken away to illustrate the interior mechanism, and

Fig. 3 is an enlarged fragmentary cross sectional view taken on the line 3—3 of Fig. 2.

In the printing industry it is common to employ metallic dust, such as aluminum, bronze, etc., which is spread over freshly printed surfaces. This dust is exceedingly fine and adheres to the damp printing ink, thus producing the metallic effect often seen on circulars and the like. Due to the fineness of this dust, great difficulty has been experienced in recovering the excess material, the very nature of which causes slight drafts to dissipate the dust over large areas, and in printing plants this dust in settling may ruin a large amount of material even sifting 40 through cracks in doors and being tracked to outside rooms, so that some of the losses have been very excessive. At the present time it is the practice to suck this material into a funnel-shaped container, but this is only a partial recovery and at the point of air escape from the suction device much material escapes.

Applicant has, therefore, devised an arrangement wherein his apparatus is connected to the suction pickup through the medium of a pipe 5, which is tangentially connected to a drum 6, which is positioned horizontally as illustrated in Figs. 1 and 2. At the bottom of this drum is formed a series of outlet pipes 7. To these outlet pipes 7, fabric sleeves 8 are secured. Positioned beneath the drum 6 and spaced therefrom

is a funnel-shaped member 9, having an upper surface 11, which carries pipes 12 communicating with the interior of the funnel. These pipes 12 correspond to the pipes 7 and are of the same number and in alignment therewith. Therefore, the fabric sleeves 8 may have their lower ends connected to the pipes 12. Secured to the bottom of the funnel is a receptacle 13 to receive the recovered material. A vent or breather pipe 14 extends through the drum 6 and into the funnel 9, its lower end extending into the funnel a considerable distance. A screened cap 16 is secured to the top of the pipe 14, the purpose of which will be later seen. The surface 11 has resting thereon an upstanding pile blanket 17. This blanket may be plush or carpet material. Surrounding the device and extending between the drum 6 and upper end of the funnel 9 is a covering 18, also made of the same material as the blanket 17 and having its pile extending toward the center of the device.

The result of this construction is that when the exhaust from the suction device enters the pipe 5 it empties into the drum 6 with a somewhat circular motion so that the material within the drum 6 is kept agitated and as the only means for escape of the air is down the pipes 7 it is apparent that the laden air will take this course. As soon as the air engages the sleeves 8 some of the air will pass through the sleeves, thus decreasing its velocity. The length of these sleeves 8 is such that the velocity at the lower end is practically nothing and therefore any dust within the sleeves will drop by gravity into the funnel 9 and be deposited in the container 13. Any excess air will escape through the pipe 14 and screen 16. However, the upward flow of air through this pipe 14 is not sufficient in velocity to cause any turbulence in the funnel 9 and consequently escapes free of any dust content. The screen 16 is merely for the purpose of preventing any eddy currents being set up by drafts blowing down or across the end of the pipe 14. It is obvious that due to the fineness of this dust, some small portion thereof will filter through the sleeves 8 and would escape to the surrounding atmosphere were it not for the blanket 17 and covering 18. The pile of the covering and blanket allows the fine particles to settle into the pile and to, therefore, be retained when the covering is removed. Were it not for the pile of the covering, the mere act of removing the covering would cause a cloud of fine material to be dissipated about the plant, irrespective of how careful the person, cleaning the device, might be.

It will thus be seen that I have produced a device which will accomplish the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a device of the character described, a drum adapted to receive dust laden air, pipes extending downwardly from said drum, a funnel-shaped container positioned beneath said drum and spaced therefrom, the upper surface of said funnel-shaped member being closed and having pipes extending therefrom and communicating with the interior of said funnel, fabric sleeves extending between the pipes of said drum and funnel, a blanket supported on the closed end of said funnel, said blanket having an upstanding

pile, and a breather pipe extending into said funnel and extending to a point above the top of said drum.

2. In a device of the character described, a drum adapted to receive dust laden air, pipes extending downwardly from said drum, a funnel-shaped container positioned beneath said drum and spaced therefrom, the upper surface of said funnel-shaped member being closed and having pipes extending therefrom and communicating with the interior of said funnel, fabric sleeves extending between the pipes of said drum and funnel, a blanket supported on the closed end of said funnel, said blanket having an upstanding pile, a breather pipe extending into said funnel and extending to a point above the top of said drum, and a covering surrounding said device and extending between said drum and said funnel, said covering having pile formed upon its inner surface.

MAXIME J. BRIZARD.
